UNITED STATES PATENT OFFICE.

HENRY DREYFUS, OF BASEL, SWITZERLAND.

MANUFACTURE OF ACETIC ALDEHYDE.

1,361,974.

Specification of Letters Patent. Patented Dec. 14, 1920.

No Drawing.

Application filed June 4, 1917. Serial No. 172,795.

To all whom it may concern:

Be it known that I, HENRY DREYFUS, of Basel, Switzerland, have invented certain new and useful Improvements Relating to 5 the Manufacture of Acetic Aldehyde, of which the following is a specification.

This invention relates to the manufacture of acetaldehyde by processes wherein acetylene is passed into sulfuric acid solutions 10 containing mercury compounds, and in particular to the manufacture of acetaldehyde by the process described in the specification of application for United States Patent Serial No. 172,325 (filed June 1, 1917), 15 which process permits of the industrial manufacture of acetaldehyde on a large scale and with a high yield of acetaldehyde relatively to the quantity of mercury compound employed.

20 The process of said application consists briefly in first producing an acid solution containing sulfate of mercury, then passing pure acetylene gas thereinto, slowly at first, and when the solution turns black or grayish-black, as rapidly as can be absorbed, then as soon as the avidity of the solution for the absorption of acetylene drops off somewhat, stopping the introduction, then distilling off the acetaldehyde formed (this 25 being best effected in a vacuum) again cooling the liquor and repeating alternately the two steps of introducing acetylene and distilling the acetaldehyde from the liquid.

In my said specification Serial No. 172,325 35 considerable importance is attributed to the apparatus employed for the manufacture of acetic aldehyde, and for the manufacture on a large scale it was proposed to employ, for the vessels or apparatus, leaden surfaces 40 which had been treated in a certain manner whereby they are enabled to resist both the action of the dilute acid present and amalgamation with mercury.

Iron, as is known, is the only common metal which does not give an amalgam with 45 mercury, but it has the disadvantage that it is attacked and dissolved by acids, so that its employment alone would be impossible.

As the result of further researches I have now found that certain alloys of iron and 50 silicon withstand dilute acids such as dilute boiling sulfuric acid, and at the same time have the advantage of not forming an amalgam when employed for apparatus for processes of the character referred to. This is 55 a surprising fact and of great technical importance.

By this invention it is possible to replace lead surfaces covered with a layer prepared as described in my said specification Serial 60 No. 172,325 by ferro-silicon employed for the apparatus or parts thereof exposed to the absorption solution.

It is thus possible to employ apparatus of very large capacity, say 1000 to 10,000 65 liters or more, made of cast iron alloyed with silicon. Suitable alloys for the purpose of the invention may contain for example 12 to 17 per cent. of silicon.

I claim:

70 In the manufacture of acetaldehyde by passing acetylene into sulfuric acid solutions containing mercury compounds, the improvement which comprises carrying out the reaction in apparatus made with iron-silicon alloys which are resistant to dilute boiling sulfuric acid and at the same time do not amalgamate with mercury.

In witness whereof I have hereunto signed my name in the presence of two subscribing 80 witnesses.

HENRY DREYFUS.

Witnesses:

THOMAS LAING WHITEHEAD,
ROBERT MILTON SPEARPOINT.
